UNITED STATES PATENT OFFICE.

FREDERICK THOMAS, OF PHILADELPHIA, PENNSYLVANIA.

SEWING-MACHINE ATTACHMENT.

1,360,598.

Specification of Letters Patent. Patented Nov. 30, 1920.

Application filed May 6, 1920. Serial No. 379,291.

To all whom it may concern:

Be it known that I, FREDERICK THOMAS, a citizen of the United States, residing at Philadelphia, in the county of Philadelphia and State of Pennsylvania, have invented a new and useful Sewing-Machine Attachment, of which the following is a specification.

The principal object of the present invention is to provide a simple, comparatively inexpensive and efficient attachment for sewing machines which can be readily put into and out of action and by means of which elastic tape can be inclosed and sewed throughout its length in a twice folded hem, either to form gathers in which the tape is stitched or to form an inelastic portion in which the tape is stitched, as desired, and this either in tubular or slotted work.

20 The invention will be claimed at the end hereof but will be first described in connection with the embodiment of it chosen from other embodiments for the sake of illustration in the accompanying drawings forming part hereof and in which—

Figure 1, is a front view of a sewing machine equipped with an attachment embodying features of the invention.

Fig. 2, is a perspective view showing the attachment and parts of the machine upon an enlarged scale.

Fig. 3, is a diagrammatic view illustrative of the product of the attachment.

Fig. 4, is a top or plan view of the attachment including at the top a sketch of the outline of the outlet end of the attachment.

Fig. 5, is a diagrammatic view showing the elastic tape in the form it assumes in going through the attachment.

40 Fig. 6, is an elevational view of the inlet end of the attachment.

Fig. 7, is a top or plan view partly in section.

Fig. 8, is a diagrammatic view showing how the elastic tape in turning folds the fabric around it in passing through the attachment, and

Fig. 9, is a schematic view of a finished product.

50 In the drawings 1, collectively is a foot arranged in advance of the needle and consisting of a tube 2, split as at 3, and provided at the edges of the split with spaced

superposed plates 4 and 5, between which the body of the fabric passes and of which the upper plate 5, extends partly across the tube and is provided with a vertical tape-guide wall 6, Fig. 7. The outlet 7, of the tube, see top of Fig. 4, is generally oblong and horizontal and the tape inlet 8, of the tube consisting in part of the wall 6, Fig. 2, is generally vertical, so that the elastic tape a , in passing through the tube is given a quarter turn in the direction indicated by the arrow in Fig. 8. The upper plate 5, is shown as also provided with a horn or guide 9^b, arranged at the inlet of the tube with space at 9^c, for the passage of the tape, and it serves as a guide or help for the operator in feeding the edge of the goods b , with an initial fold into the tube. 9, is a manually operated friction tension lever pivoted to the plate 5, as at 10, and provided with a tape feed inclosed channel 11, slightly warped out of the vertical, and with a tension finger 12, that co-operates with the vertical wall 6, to free and to retard the passage of the tape. 13, is an adjustable stop for the lever 9. 14, is a bracket applied to the head of the sewing machine by slot and screw connection 15, so that vertical adjustment is provided. 16, is an arm turnable on the bracket in respect to or toward and away from a stop screw 17, and at its lower end it is connected with 80 the foot 1, by screw and hole connection 18.

To finish, for example, the top of a petticoat with an elastic tape, the elastic tape is run through the tube 2, along with the edge of the top of the petticoat, so that the quarter turn imparted to the tape in co-operation with the tube 2, puts the tape inside of a fold in the goods after the fashioning of a hem in which the goods or stuff is folded twice. If lever 9, is turned to free the passage of the elastic tape, *i. e.* clockwise in Fig. 7, and is held in such position, the stitches x , Fig. 3, catch not only the elastic tape but also the goods, see y , Fig. 3, and by reason of the absence of retardation of the 90 tape inelasticity is produced as at c , Fig. 9, in the product such as is appropriate for the front of the petticoat and for the parts adjoining the placket, where the fastening devices are applied. If the lever 9, is released it is turned by the drag of the tape 100 105

in the other direction and its finger 12, retards the passage of the elastic tape and this elongates or stretches the tape but it is nevertheless caught by the stitches α , see α , 5 in Fig. 3, and when the fabric and tape are released from tension the elastic tape contracts and the goods are gathered as indicated at d , Fig. 9, and this is appropriate for the side portions of a petticoat.

10 The attachment can be swung up out of action into the position indicated by dotted lines in Fig. 1, and this is advantageous when plain sewing is to be done, and also in connection with finishing tubular articles 15 in the manner described, for example, the knees of bloomers which are not provided with plackets but are tubular. In the case of such articles the work is done in the manner described by means of the attachment 20 nearly around the article, then the attachment is put out of action and the little remaining work is done by hand feeding and folding.

Inasmuch as the tape is always in the 25 path of the stitching mechanism it is stitched throughout the length and at all points of the hem and in this way the seam is equally strong throughout the length of the hem.

30 It will be obvious to those skilled in the art that modifications can be made in details of construction and arrangement without departing from the spirit of the invention, which latter is not limited as to such matters 35 or otherwise than as the prior art and the appended claims may require.

I claim:

1. A sewing machine attachment comprising in combination a support consisting of 40 a bracket and an adjustable swinging arm arranged for attachment to a sewing machine head, a foot carried by the arm and arranged in advance of the needle, an elastic-tape and fabric guide provided in the 45 foot and consisting of a generally upright tape guide wall and a fabric and tape receiving tube having a generally horizontal outlet whereby the tape is given a quarter turn which wraps the fabric around it, and a 50 friction tension lever provided on the foot and adapted to be moved to apply tension to the tape to stretch and to release the tape while in the path of the stitching.

2. A sewing machine attachment comprising in combination a support consisting of 55 a bracket and an adjustable swinging arm arranged for attachment to a sewing machine head, a foot carried by the arm and arranged in advance of the needle, an elastic-tape and fabric guide provided in the 60 foot and consisting of a generally upright tape guide wall and a fabric and tape receiving tube having a generally horizontal outlet whereby the tape is given a quarter 65 turn which wraps the fabric around it, a

friction tension lever provided on the foot and adapted to be moved to apply tension to the tape to stretch and to release the tape while permitting the needle to at all times penetrate the tape, and a guide spaced 70 from the wall for the passage of the tape and projecting from the inlet of the tube into the line of feed of the fabric, substantially as described.

3. A sewing machine attachment comprising in combination, a foot consisting of a split tube having a horizontal outlet and provided at the edges of the split with spaced superposed plates between which the body of the fabric passes and of which the 80 upper plate projects in the tube, a vertical tape-guide wall provided on the upper plate and that co-operates with the horizontal outlet to give the tape a quarter turn, a fabric-folding guide provided on the upper plate 85 and arranged at the entrance of the tube and spaced clear of the wall, means for applying and releasing tension in respect to the tape, and devices for positioning the foot when operative for inserting tape to feed 90 the tape at all times into the path of the stitching, substantially as described.

4. A sewing machine attachment comprising in combination, a foot consisting of a split tube having a horizontal outlet and 95 provided at the edges of the split with spaced superposed plates between which the body of the fabric passes and of which the upper plate projects in the tube, a vertical tape-guide wall provided on the upper plate 100 and that co-operates with the horizontal outlet to give the tape a quarter turn, means for applying and releasing tension in respect to the tape, and devices for positioning the foot, when operative for inserting tape, to 105 feed the tape at all times into the path of the stitching, substantially as described.

5. A sewing machine attachment comprising the combination of a foot provided with a fabric folding tube having a horizontal 110 outlet and a vertical elastic-tape inlet feed whereby the tape in taking a quarter turn wraps the fabric around it preparatory to sewing, and a pivotal manually shifted tension lever provided on the foot and held in 115 action by the tape, substantially as described.

6. A sewing machine attachment comprising the combination of a foot provided with a fabric folding tube having a horizontal 120 outlet and a vertical elastic tape inlet feed whereby the tape in taking a quarter turn wraps the fabric around it preparatory to sewing, a freely movable pivotal tension lever provided on the foot and manually held out of action and held in action by the 125 tape, and a movable bracket arm carrying the foot and adapted to position it in operative and inoperative positions, substantially as described.

7. In an attachment of the class specified 130

for sewing machines the combination of a foot split for the passage of the work and comprising a tube having an oblong horizontal outlet and top and bottom plates between which the body of the work passes, a vertical tape-guide wall provided on the top plate and constituting with the tube a verti-

cal tape entrance, and a manually operated friction tension lever pivoted to the top plate and provided with a tape-feed in- 10 closed channel and with a tension finger adapted to coöperate with the vertical wall, substantially as described.

FREDERICK THOMAS.
